UNITED STATES PATENT OFFICE.

WILLIAM H. BINDER, OF SAN LUIS OBISPO, CALIFORNIA.

SPREADER.

1,299,666.

Specification of Letters Patent.

Patented Apr. 8, 1919.

Application filed November 15, 1916. Serial No. 131,562.

To all whom it may concern:

Be it known that I, WILLIAM H. BINDER, a citizen of the United States, residing at San Luis Obispo, in the county of San Luis Obispo, State of California, have invented certain new and useful Improvements in Spreader; and I do declare the following to be a full, clear, and exact description of the same, reference being had to the accompanying drawings, and to the characters of reference marked thereon, which form a part of this application.

This invention relates to improvements in sand and gravel spreaders adapted for use in connection with wagons or trucks designed for carrying sand or gravel for distribution over highways or similar places. The object of the invention is to produce a spreader which will keep the sand or gravel in continual motion and equally distributed over the surface of the street or highway or other places in an even and proportionate manner and in such quantities as may be desired. Also the invention embodies means for evenly spreading material along the shoulders of the road which is very essential in the making up and keeping up of highways. The invention is designed to do away with the necessity of manually spreading the sand or gravel as is now the most common practice. My improved structure is attached directly to the wagon or truck and the distributing shaker is operated by being connected with any suitable driving means connected with the wheels or driving parts of the vehicle.

A further object of the invention is to produce a simple and inexpensive device and yet one which will be exceedingly effective for the purposes for which it is designed.

These objects I accomplish by means of structure and relative arrangement of parts as will fully appear by a perusal of the following specification and claim.

In the drawings similar characters of reference indicate corresponding parts in the several views.

Figure 1 is a rear elevation of my improved structure.

Fig. 2 is an end view of the same.

Fig. 3 is a detached fragmentary view of the distributing shaker used in connection with the spreader.

Referring now more particularly to the characters of reference on the drawings, my improved spreader consists primarily of a container 1 which may be suitably connected

with a truck or wagon in any manner found most desirable. The front end of the container 1 is opened as at 2 to allow of the material being filled therein from the truck or wagon in any suitable way or manner.

The rear end of the container 1 is open and such open end is controlled by a slideable door plate 3 movable between guides 4 and 5. On the door plate 3 are rigidly fastened bearings 6 movable vertically in slots 7 formed in the side walls of the container 1. Arranged for sliding motion in the bearings 6 is a shaker rod 8 having inwardly projecting shaker teeth 9. This shaker rod 8 as shown in Fig. 1 extends immediately along the lower edge of the door plate 3.

Reciprocating motion is applied to the rod 8 by means of the following structure, 75 namely: A beveled gear 10 is suitably driven by another beveled gear 11 which in turn is driven by the sprocket wheel 12, which sprocket wheel is connected by suitable chains to any desired source of power such as the jackshaft on a motor truck or any other suitable driving means found desirable according to the form of vehicle used. A wrist pin 13 is mounted on the back side of the gear 10 and a connecting rod 14 connects the wrist pin 13 with another wrist pin 15 on the arm 16 secured to the outer end of the rod 8. As is apparent, the rotation of the gear 10 will, through the medium of the connecting rod 14 form a reciprocating motion to the said rod 8.

In practice the sand or gravel is delivered into the container 1 in any suitable manner, and, with the agitation of the same by the action of the rod 8 and its teeth 9, it is continually delivered and distributed equally through the outlet space 17 between the lower side of the rod 8 and the bottom of the container 1. This space 17 may be made larger or smaller by the raising or lowering of the door plate 3 to which the bearings for the rod 8 are attached as noted above. This movement of the door plate 3 is accomplished by means of the following structure, 95 namely:

Between the sides of the container 1 at the back thereof is secured an angle iron 18 between the sides of which are two or more nuts 19. At the upper edge of the door plate 3 are flanges 20. Turnable in each flange 20 is a crank handle 21. Each crank handle 21 has a projecting threaded pin 22 thereon, which pins 22 are threaded through the nuts 19. Thus with the turning of the

crank handles 21 these threaded pins 22 will advance through the nuts 19 in one direction or the other. The crank handles 21 have no vertical movement through the flanges 20 and hence as the said pins 22 advance through the nuts 19, the door plate 3 will be raised or lowered which will increase or diminish the size of the space 17. The bearing members 6 during this operation move through the slots 7.

From the foregoing description it can be readily ascertained that I have produced a very efficient and effective spreader for sand and gravel and one which can be operated automatically and easily by attaching it to the rear end of a truck or wagon carrying the material. The use of such a spreader will eliminate a lot of labor and expense incurred by the ordinary method of spreading the material by hand from piles or from a vehicle.

From the foregoing description it will also be readily seen that I have produced such a device as substantially fulfills the object of the invention as set forth herein.

While this specification sets forth in de-

tail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

A spreader comprising a container having its rear end open, a vertical door plate adjustably and slidably mounted in said open end, downwardly projecting bearings fixed at the sides of the door plate and movable therewith, a shaker rod arranged for reciprocating motion in the bearings immediately under the door plate and adapted to bear against the bottom of the container when the door is at its downmost position, means for reciprocating said shaker rod and teeth on the shaker rod projecting horizontally into the container.

In testimony whereof I affix my signature.

WILLIAM H. BINDER.
